WILLIAM TUNSTILL, OF PATERSON, NEW JERSEY.

Letters Patent No. 65,309, dated May 28, 1867.

IMPROVEMENT IN BRAIDING MACHINES.

The Schedule referred to in these Letters Patent and making part of the same.

TO ALL WHOM IT MAY CONCERN:

Be it known that I, WILLIAM TUNSTILL, of Paterson, in the county of Passaic, and State of New Jersey, have invented, made, and applied to use, a certain new and useful Improvement in Braiding Machines; and I do hereby declare the following to be a full, clear, and exact description of the said invention, reference being had to the annexed drawing, making part of this specification, wherein—

Figure 1 is an elevation showing a braiding machine with only three spools or bobbins, and illustrating my improvement; and

Figure 2 is a plan, below the line x x , one of the bobbins and its case being shown in section.

Similar marks of reference denote the same parts.

In braiding machines it is usual to have the bobbin or spool-carriers travel through an 8-shaped slot, or through a series of such slots, the thread passing off the spool beneath or through a weight that takes up the slack thread when the carrier is nearest to the point where the braiding takes place. This causes considerable strain and wear on the threads and strands, so that in practice it is found that the braiding machines cannot be used with threads finer than a certain size. Besides this, the tension is rendered irregular in consequence of the thread passing off, sometimes at right angles to the spool and at others above or below that point, as the thread unwinds from or towards the ends of the spool.

The nature of my said invention consists in an automatic let-off and weighted pulley, combined with a bobbin or cap, in which the thread is taken off at or near the line of the axis, thereby enabling me to occupy much less room or horizontal space than has heretofore been required for effecting the movements of the bobbins in braiding, and the friction and wear on the thread are entirely avoided by the pulley, as that turns with the thread, and the tension is rendered uniform at all times, so that there is very little liability for the thread to break. And I enclose the bobbin or cap in a case so that the thread is kept from the dust and dirt, and the machine may be allowed to stand over night, or for a number of days, without the exterior layer of thread becoming soiled, as heretofore usual, particularly with silk and other delicate threads.

I make use of a friction mechanism between the driving-pulley and the main shaft of the machine, in connection with the stopping and starting lever, so that the starting will be gradual and not liable to break the threads as with the positive gearing heretofore employed.

In the drawing a represents the slotted plate, b the drivers, with notches in their edges taking the pins c on the under sides of the bobbin-carriers d , and e e are the driving-wheels, all as usual; and I here remark that the number of bobbins may be increased indefinitely, and the shape of the slot in the plate a may be varied as desired. f is a bevelled friction-pulley below the wheel g , and h is a similar friction-pulley contiguous to and rotated by the driving-pulley k . The surfaces of either or both these friction-wheels, f and h , are covered with leather so as to produce the requisite friction when pressed into contact. The pulley f is set upon a feather on shaft l , or otherwise connected thereto, so that a slight movement may be given thereto for producing or relieving the friction with h , and a lever l' is provided to act upon said pulley f through the washer of India rubber i and a metal washer next the pulley f , so that the yielding of said rubber washer i shall allow for any inequalities in the friction surfaces of f and h . The lever l' is raised for starting the machine and dropped for stopping it, the starting being gradual in consequence of the friction. The pulley k has a flat belt passing to the main driving-shaft, as in Letters Patent granted to me August 19, 1862. The lever l' has at its end a latch-bar, m , that passes up and takes over the lever m' , which is acted upon by the base of the weighted pulleys hereafter described. In case said pulley falls by the breaking of a thread, and unlatching the lever m' from the bar m , allows the lever l' and pulley f to drop out of contact with h . The shaft l is continued up and gives motion to any desired character of take-up for the braided fabric. I have shown the worm n , wheel and shaft n' , and barrel n'' , around which the braided material passes once or twice and thence goes to the winding-reel n^3 driven by a friction-belt to a pulley, n^4 , on the shaft n^1 . o is the eye through which the braided fabric passes. Upon each bobbin-carrier I affix a case, p , of sheet metal, having on one side a swinging door or flap, through which the bobbin or cap p' is entered. The thread passes off from said bobbin or cap around a grooved ratchet-wheel, q , held by a pawl, 2 , and its spring 3 . The case p is to be of a size and shape adapted to the cap. r^2 is the pulley, with the weight r set to slide vertically on suitable guide-rods r^1 , which also aid in sustaining upon their upper ends the frame that

supports the ratchet-wheel q and its pawl. The thread passes from q down to and below the grooved pulley r^2 , and thence upward and out through the eye 4 above. The weight r of the pulley r^2 also forms its support and guide, and may be increased by the addition of weights, each made with a hole in its centre and placed over a stud, 5, on the base of r . A finger, 6, projects upward from the slide-weight r , and when the tension of the thread lifts the weight r sufficiently, said finger 6 comes into contact with the pawl 2, and lifting the same allows the grooved ratchet-wheel q to turn by the action of the thread wound around it, and thereby causing the weight to descend as the thread is given off. The pawl 2 again entering the ratchet q holds the thread as before, until the braiding operation, again drawing off the thread, raises the pulley r^2 and finger 6 into contact with the ratchet q . It will be seen that this weight and let-off might be used with a cop or bobbin and without the case, and in consequence of the pulley r^2 preventing friction and wear on the thread, a much greater weight and tension may be employed without risk of breaking the thread. The pulley r^2 , weight r , grooved ratchet q , and pawl 2 may be employed as a warp-regulator in a loom, to keep a definite strain upon one or more warps passed around said ratchet-wheel q and beneath the pulley r^2 , and let the same off from time to time as the weaving or braiding progresses. The thread in my machine being drawn off from the end of the cop, uncoils without friction and with regularity, the same as in an ordinary shuttle, and there is no liability to break or become wedged in between the other threads as there is in the usual braiding machines where the thread is drawn off from the side of the spool against the friction and stop-motion applied to prevent the spool turning.

What I claim, and desire to secure by Letters Patent, is—

1. The case p fitted upon the carrier d in a braiding machine, and containing the bobbin or cop from which the thread passes off, upon the line, or nearly so, of the axis of said bobbin or cop, substantially as and for the purposes set forth.
2. I claim the ratchet-pulley q over which the thread passes, pawl 2, and finger 6, in combination with the weight r , substantially as and for the purposes specified.
3. I claim the grooved ratchet-wheel q over which the thread passes, pawl 2 and weight r , in combination with the cop and bobbin p' , substantially as and for the purposes specified.
4. I claim friction-wheels applied in substantially the manner specified between the driving-pulley k and the main shaft l of a braiding machine in combination with the stopping and starting mechanism, so that the machine may commence to move gradually instead of suddenly, as set forth.

In witnesss whereof I have hereunto set my signature this 27th day of August, A. D. 1866.

WILLIAM TUNSTILL.
